UNITED STATES PATENT OFFICE.

ROMAN C. SMOCZYNSKI, OF CATAWISSA, PENNSYLVANIA.

BLOCKS FOR PORTABLE MACHINERY.

1,250,374.

Specification of Letters Patent. Patented Dec. 18, 1917.

Application filed March 16, 1917. Serial No. 155,371.

To all whom it may concern:

Be it known that I, ROMAN C. SMOCZYNSKI, a citizen of the United States, residing at Catawissa, in the county of Columbia and State of Pennsylvania, have invented certain new and useful Improvements in Blocks for Portable Machinery; and I do hereby declare the following to be a full, clear, and exact description of the invention such as will enable others skilled in the art to which it appertains to make and use the same.

This invention relates to blocks or chocks for preventing movement of portable machinery, such as portable gasolene engines, traction engines, grain separators or other analogous portable machinery wherein belt power is employed for operating the same, or from which power is transmitted by belt.

An object of this invention is to provide a block structure as specified which includes a pair of blocks adapted to be slipped beneath the rear wheels of portable machinery as specified which blocks are carried by the lower ends of pivotally mounted arms, to provide bracing arms for the blocks which are pivotally connected to the axle of the portable machine and further to provide a rock shaft to which the arms which carry the blocks are connected, so that upon the rocking of the shaft the blocks will either be forced beneath the wheels or moved out from the wheels and upwardly out of the ground engaging position.

With the foregoing and other objects in view, this invention consists in such novel features of construction, combination and arrangement of parts as will be hereinafter more fully described, illustrated in the accompanying drawings and claims.

In describing the invention in detail, reference will be had to the accompanying drawings wherein like characters designate like and corresponding parts throughout the several views, and in which:—

Figure 1 is a side elevation of a portable gasolene engine showing the improved block attachment thereto and having the wheels of one side removed;

Fig. 2 is a bottom plan view of a fragment of a portable machine showing the invention applied;

Fig. 3 is a fragmentary section on the line 3—3 of Fig. 2; and

Fig. 4 is a detail perspective view of the chock or block attachment.

Referring more particularly to the draw-

ings, 1 designates the chassis or supporting frame of a portable gasolene engine of any ordinary type and while the invention is shown applied to this particular type of portable machinery, it is to be understood that it may be applied to any type of portable machinery or vehicle as desired without departing from the spirit of this invention.

The supporting frame 1 of the portable machine has a rear axle 2 carried thereby upon the spindle ends of which the usual type of supporting wheels 3 are mounted. The side rails 4 and 5 of the supporting frame 1 are provided with cutout portions 6 formed therein and extending upwardly from their under surfaces adjacent their rear ends in which cutout portions is slidably mounted a cross bar 7. The bar 7 may be of the usual type of brake beam. The cross bar 7 has a plurality of depending bearing brackets 8 carried thereby which rockably support a shaft 9 that extends transversely across the machine and has a U-shaped bracket 10 depending from each end 80 of the same and a third substantially U-shaped bracket 11 depending from the center of the shaft as clearly shown in Fig. 4 of the drawings. The depending U-shaped bracket 10 has links 12 pivotally connected thereto as shown at 13 to the lower ends of which links are connected the blocks 14 which are adapted to be moved beneath the rear wheels 3 for blocking or chocking these wheels so as to prevent accidental movement 90 of the portable machinery during its operation. The chocking blocks 14 have their upper surfaces convexedly curved as shown at 15 and 16 and concavely curved as shown at 17 intermediate the two convexedly curved 95 portions for securely fitting beneath the rear wheels and blocking them up out of ground engaging position.

Links 18 are connected as shown at 19 to the blocks 14 and they are pivotally connected as shown at 20 to blocks 21. Pins 22 are formed upon and extend forwardly from the front ends of the blocks 21 which pins extend through the rear axle 2 inwardly of the spindle ends of the axle as clearly 105 shown in Fig. 2 of the drawings. The links 18 are pivotally connected to the blocks 21 and 14 and they are provided for bracing the blocks.

The depending centrally disposed U-shaped bracket 11 has a rod 24 pivotally connected thereto which rod is also pivot-

ally connected to a U-shaped bracket 25 which depends from the enlarged portion 26 of a rock shaft 27. The rock shaft 27 is rockably supported by suitable bearings 5 28 which are carried by the supporting frame 1. A hand lever 30 is mounted upon the rock shaft 27 for rocking this shaft.

When the portable machine has been transported to a desired location, and it is 10 to be employed either for transmitting power to another machine, or for performing the function for which it was designed, the hand lever 30 is rocked, which will rock the shaft 27 and consequently rock the rock shaft 9, 15 through the medium of the rod 24. The rocking of the shaft 9 will, when the hand lever 30 is moved forwardly, move the links 12 rearwardly and force the blocks 14 beneath the rear supporting wheels 3 of the 20 portable machine, preventing these wheels from rotating during the operation of the machine and also eliminating the necessity of blocking the wheels of the machine in the usual manner.

From the foregoing description taken in 25 connection with the accompanying drawings, the advantages of construction and of the method of operation of the improved block for portable machinery, will be readily 30 apparent to those skilled in the art to which this invention appertains, and while in the foregoing description, the principle of the operation of this invention has been described together with various features of 35 construction, it is to be understood that certain minor features of construction, combination and arrangement of parts may be altered to suit practical conditions provided such alterations are comprehended within 40 the scope of what is claimed.

What is claimed is:—

1. The combination with a portable machine including a supporting structure, a rear axle, and supporting wheels mounted

upon said axle, of a rock shaft rockably carried by said supporting structure, a pair of links pivotally connected to the ends of said rock shaft, chocking blocks pivotally connected to the lower ends of said links, a second rock shaft carried by said supporting structure, a lever attached to said second named rock shaft, means connecting said first named rock shaft and said second named rock shaft for rocking the second named rock shaft upon pivotal movement of 55 said lever for forcing said blocks beneath the rear supporting wheels and means connected to said axle and said chocking blocks for guiding the movement of the blocks and holding them predetermined distances from 60 said axle.

2. The combination with a portable machine including a supporting structure, a rear axle, and supporting wheels mounted upon said axle, of a rock shaft rockably carried by said supporting structure, a pair of links pivotally connected to the ends of said rock shaft, chocking blocks pivotally connected to the lower ends of said links, a second rock shaft carried by said supporting structure, a lever attached to said second named rock shaft, means connecting said first named rock shaft and said second named rock shaft for rocking the second named rock shaft upon pivotal movement 70 of said lever for forcing said blocks beneath the rear supporting wheels, links pivotally connected to said blocks, blocks pivotally connected to the upper ends of said last named links, pins carried by said last named 75 blocks and extending through said rear axle.

In testimony whereof I affix my signature in presence of two witnesses.

ROMAN C. SMOCZYNSKI.
